CLAIM

The ornamental design for a decanter as shown and described.

DESCRIPTION

1.1 : Top

1.2 : Bottom

1.3 : Right

1.4 : Front

1.5 : Back

1.6 : Perspective

The product is a glass decanter of a round shape used for storing and serving alcohol drinks, in particular whisky; the views are as follows: **1.1** Top view, **1.2** Bottom view, **1.3** Right view, **1.4** Front view, **1.5** Back view, **1.6** Perspective (front, top, right) view; the left view is omitted because it is identical to the right view.
